UNITED STATES PATENT OFFICE.

SHERIDAN S. BIGLER, OF NEW PHILADELPHIA, OHIO.

AUXILIARY MOTOR CUT-OFF FOR PRESSURE SYSTEMS.

Application filed January 26, 1924. Serial No. 688,887.

To all whom it may concern:

Be it known that I, SHERIDAN S. BIGLER, a citizen of the United States, residing at New Philadelphia, in the county of Tuscarawas and State of Ohio, have invented certain new and useful Improvements in Auxiliary Motor Cut-Offs for Pressure Systems; and I do declare the following to be a full, clear, and exact description of the invention, such as will enable others skilled in the art to which it appertains, to make and use the same.

My invention relates generally to pressure systems for handling water, air, or any other liquid or fluid, but it is my primary intent to improve upon water-pumping systems of the type in which a motor-driven pump is employed for forcing water into a tank and compressing air in this tank, so that the air pressure may be used to discharge the water. Pressure systems of this character are provided with an automatic pressure-operated switch for cutting off the pump motor when the pressure has reached a predetermined degree, but automatic switches of this nature very often fail to operate, and hence, the excess pressure must escape through a blow-off valve, but no provision is made for then stopping the motor, with the result that the latter often runs continuously for long periods of time, with very detrimental results.

It is the principal object of the invention to provide an auxiliary, pressure-operated cut-off for the pump motor which is adapted to come into play at a higher pressure than the usual automatic cut-off, whereby to stop the motor in case the ordinary cut-off fails to function.

Pressure systems of the type to which I have referred are commonly provided with a manually operated switch in the current supply line for the pump motor, and it is a further object to provide the auxiliary cut-off means of such form as to operate this hand switch to obtain the desired results.

Yet another object is to provide a work-producing device operated by escaping pressure from the usual pressure blow-off of the system, said work-producing device being primarily intended for stopping the pump motor, although it might in some instances be utilized for other purposes, for instance, to sound an alarm and thus give warning that the automatic switch has not

operated and that pressure is escaping through the blow-off valve.

A still further object is to provide a simple and inexpensive construction which may be quickly and easily attached to the ordinary blow-off valve of a pressure system.

With the foregoing in view, the invention resides in the novel subject matter herein-after described and claimed, the description being supplemented by the accompanying drawing.

Figure 1 is a diagrammatic view showing a water pumping system embodying my improvements.

Figure 2 is an enlarged side elevation of the pressure blow-off valve, the attachment connected therewith, and associated parts.

Figure 3 is an enlarged vertical sectional view through the parts shown in Fig. 2.

Figure 4 is a sectional view similar to the upper portion of Fig. 3 and illustrating the manner in which the attachment operates.

In the drawing above briefly described, the numeral 1 designates an air and water tank, 2 represents a pump connected with the tank by piping 3, 4 has reference to the operating motor for the pump 2, and 5 indicates an automatic pressure-operated cut-off switch for the motor 4. At 6, a hand-operated switch is provided for entirely cutting off the flow of current to the motor 4 whenever desired, said switch 6 being shown of the usual knife type, having an operating handle 7 at one end.

Connected with the piping 3, I have shown a pressure blow-off valve 8 which is adapted to come into play in case the automatic switch 5 fails to function, and it will be understood that this valve may be connected with any desired part of the system and is not necessarily connected with the piping 3. In the present disclosure, I utilize the pressure escaping through the exhaust port 9 of the valve 8, for the purpose of opening the switch 6. In obtaining this result, I connect a cylinder 10 with the port 9, for instance, by an elbow 11 which may well have a pet-cock 12. While not necessarily so, I have illustrated the cylinder 10 standing upright and provided at its upper end with a cap 13. Through this cap, a rod or stem 14 passes, said stem being connected to a piston 15 in the cylinder 10, so as to be moved outwardly by

this piston, when pressure escapes through the port 9. On the outer end of the stem 14, I have shown a U-shaped seat 16 which is adapted to strike the switch handle 7 as shown in Fig. 4, thereby opening the switch when the seat is forced outwardly. To always retain this seat in proper relation with the handle, I make suitable provision for holding the rod 14 against turning and for 10 limiting its downward movement. I prefer to square the rod and the opening in the cap 13 through which it passes to prevent rotation, and to provide a pin 17 carried by the rod and adapted to strike the cap 13 to limit the descent of the rod and associated parts.

To properly mount the switch in operative relation with the stem 14 and in order that this switch may be easily installed in 20 the system, I prefer to mount it upon a suitably shaped bracket 18 which may well be clamped to the cylinder 10 by appropriate clamps 19.

When the arrangement shown and described is employed, or an equivalent arrangement, if the switch 5 fails to operate, rising pressure in the tank 1, will cause opening of the pressure blow-off valve 8 and escape of pressure through the port 9. 25 This pressure acts on the piston 15 and in the present instance, opens the switch 6 to stop the motor 4, but it is to be understood that this piston 15 or an equivalent device may be used to perform other work. For 30 instance, I may, if desired, utilize the escaping pressure from the blow-off valve to operate an alarm and thus give warning that the automatic switch 5 has not operated and pressure is high. It is preferable, to 35 have the means which is controlled by the exhaust pressure actually throw the pumping motor out of play, as the premises in which pumping systems are used, are very often vacant for different periods of time,

and there would hence be no attendant for 45 the pumping system, to give heed to any warning as to excess pressure.

As excellent results have been obtained from the general association disclosed, it is preferably followed, but within the scope 50 of the invention as claimed, numerous changes may be made.

I claim:

1. The combination with a cylinder adapted to receive pressure; of a bracket 55 having a portion contacting with the outer side of said cylinder and a portion projecting laterally from one end of the latter, means securing the first named portion of the bracket to the cylinder, a hand-closed 60 switch including a base mounted on said bracket and a handle extending across said one end of the cylinder, and a piston in said cylinder having a stem positioned to thrust outwardly upon said handle and open 65 the switch.

2. A pressure-operated switch comprising a cylinder adapted to receive pressure, an L-shaped bracket having one of its ends parallel with the cylinder and its other end 70 extended laterally from said cylinder, clamps embracing said first named end of the bracket and the cylinder to secure said bracket to said cylinder, a manually controlled knife switch mounted upon the laterally extending end of said bracket and having an operating handle spaced outwardly from and in line with the aforesaid cylinder, a pressure-operated piston in said cylinder having a rod extending to a point 75 80 adjacent said handle, and U-shaped seat carried by the outer end of said rod to engage said handle and open the switch when the piston and rod are forced outwardly.

In testimony whereof I have hereunto 85 affixed my signature.

SHERIDAN S. BIGLER.
